(57) **CLAIM**

The ornamental design for a sports wagon vehicle body, as shown and described.

DESCRIPTION

FIG. 1 is a front perspective view of the sports wagon vehicle body, showing my new design;

FIG. 2 is a rear perspective view thereof;

FIG. 3 is a side view thereof;

FIG. 4 is a front view thereof; and,

FIG. 5 is a rear elevation view thereof.

The wheels shown in broken lines are shown for illustrative purposes only and form no part of the claimed design.
